UNITED STATES PATENT OFFICE.

AAGE E. WINCKLER, OF MILWAUKEE, WISCONSIN.

INTERNAL-COMBUSTION ENGINE.

Application filed March 26, 1925. Serial No. 18,384.

The invention relates to internal combustion engines of the injection type.

One object of the invention is to provide an internal combustion engine which is adapted for use in vehicles. Another object is to provide an improved engine in which the mechanism for feeding fuel charges under pressure to the engine cylinders is driven from the engine and adapted to be attached and detached from the engine casing. Another object is to provide an improved arrangement of the fuel feed mechanism with the engine which adapts the engine for use in motor vehicles. Another object is to provide an improved fuel feeding mechanism for forcing charges into an engine of the sleeve-valve type and which is adapted for ready connection to the casing of such an engine. Other objects of the invention will appear from the detailed description.

The invention consists in the several novel features hereinafter set forth and more particularly defined by claims at the conclusion hereof.

In the drawings: Fig. 1 is a vertical transverse section of an engine embodying the invention and applied to a vehicle. Fig. 2 is a side elevation, parts being shown in section. Fig. 3 is a plan. Fig. 4 is a section through one of the engine cylinders and fuel injectors.

The invention is exemplified in an engine B of the six cylinder type with the cylinders vertically arranged and longitudinally aligned. The motor vehicle comprises sills or side frame bars a, a radiator a' for cooling the water circulated around the engine, a dash board a², a steering post a³ and a suitable hood a⁴ under which the engine and its associated parts are disposed. The casing of the engine is provided with brackets a⁵ and a⁶ which are secured to the sills a so that the engine will be supported from the sills.

The engine casing comprises a body section b and a crank-case b² which are secured together by bolts b³. Each cylinder comprises an inner wall b⁴ and an outer wall b⁵ to form a water-jacket b⁶ around the cylinders. An air inlet port b⁷ and an exhaust port b⁸ are provided for each cylinder. A crank-shaft b¹¹ is suitably journalled in the crank-casing and provided with cranks b¹² which are respectively connected by pitmen b¹⁴ to the working pistons b¹³ in the cylinders respectively. The engine is of the fuel-injection type and the upper end of each cylinder is

provided with a head C which is secured to the cylinder casting by bolts c. The engine is of the four-cycle sleeve-valve type and comprises an outer cylindrical sleeve 25 which fits in the working cylinder b⁴ and is operatively connected to an eccentric 26 on a valve-operating shaft 27 which is driven from the crank-shaft b¹¹ in the ratio of 2 to 1. Eccentric 26 is provided with an arm 28 which is pivoted at 29 to a lug on the lower end of sleeve 25 and is adapted to reciprocate said sleeve-valve in its cylinder b⁴. Each valve 25 is provided with a port 30 adapted to register with the air intake port b⁷ and with a port 31 adapted to register with the exhaust port b⁸ in the cylinder b⁴ and inner cylindrical sleeve valve 32 is slideable in the sleeve valve 26 and is reciprocated by an eccentric 33 on a shaft 27 and an arm 34 fixed to said eccentric and pivoted at 35 to a lug on the lower end of sleeve valve 32. This inner sleeve-valve is provided with an air port 36 which, when in registry with ports 30 and b⁷, will admit air into the cylinder every fourth cycle. The inner sleeve 32 is provided with a port 37 which, during every fourth cycle of the piston, is adapted to register with the exhaust port 31 in the outer sleeve valve of an exhaust port b⁸ in the cylinder b⁴. Each cylinder head C comprises a cylindrical wall c' extending longitudinally of and into the working cylinder b⁴ and the sleeve valves 25 and 32 slide between said wall and said cylinder. Each cylinder head comprises an inwardly extending wall c⁵ which is inclined inwardly and upwardly and formed with an opening c⁶. A combustion chamber c⁷ is formed in the opening c⁶ and the wall around the chamber is extended upwardly to form a cylindrical portion c¹³. The piston b¹³ has a tip c¹⁵ adapted to enter the combustion chamber. The top closure for the water jacket b⁶, which is common to all of the cylinders, is formed by a head E which is fitted to the top of the cylinder casting to form a water-space e around the cylinder-head and the combustion-chamber. Head E is secured in place by collars c⁸ which are threaded to the extensions c¹³ and engage collars e⁹.

An injector D is removably mounted in the cylindrical extension c¹³ of each cylinder-head C. Each injector D comprises a tubular casing d which extends and fits into the extension c¹³ of the cylinder head C and is provided at its upper end with an outwardly

extending flange d' . A valve d^2 , for controlling the injection of fuel into the combustion chamber, comprises a stem portion d^3 which is longitudinally grooved to permit fuel to flow to its point d^6 which is adapted to close against a conical seat d^5 in a nozzle d^4 . This nozzle is formed to spray and separate the fuel as it is injected into the combustion chamber, as well understood in the art.

A diaphragm d^9 has its outer margin clamped between the flange d' of casing d and an annular member d^{12} , which is removably secured to said flange. The inner margin of said diaphragm is clamped between an annular shoulder 49 on the valve stem and the lower end of a sleeve d^8 which is movable with the valve. The sleeve d^8 is forced into clamping relation with the diaphragm by a nut 52 which is threaded to the upper portion of the valve-stem. A chamber 48 is formed adjacent the underside of the diaphragm d^9 to expose the lower face of the diaphragm to fuel under pressure so that when the desired injection pressure is reached, the valve will be opened to inject a charge of fuel into the combustion chamber.

Member d^{12} forms a housing for a spring d^{15} , the force of which is applied to resist the movement of the diaphragm until a predetermined pressure has been reached. The upper end of this spring engages an inwardly extending flange d^{16} on member d^{12} and its lower end engages an annular shoulder d^{17} on a collar d^{18} which is screw-threaded to the lower end of the valve-sleeve d^8 . Sleeve d^8 is provided with an offset d^{19} in which is formed a conoidal seat d^{20} for a tapered plug d^{21} , which is connected by a flexible pipe d^{22} to a suitable fuel pumping and metering unit.

The fuel passes into a chamber 41 in plug d^{21} and thence downwardly through an inclined port 42 to an annular groove 43 in the valve stem. The latter is longitudinally grooved, as at 44, to conduct fuel to an annular groove 45 in the lower end of sleeve d^8 adjacent the top of the diaphragm d^9 . An inclined cross-port 46 extends through the valve stem above the shoulder 49 and the diaphragm and downwardly divergent ports 47 extend from the central portion of port 46 to the chamber or space 48 below the diaphragm d^9 . A groove 50 is formed in the stem of valve d^2 , so that fuel will flow from chamber 48 longitudinally of the grooved portion d^3 of the valve stem to the point d^6 of the valve and the nozzle d^4 .

A coupling ring 64 is adapted to connect the entire injector unit to the collar e^4 so that the injector may be uncoupled from and coupled to the cylinder head C, as a unit. This ring 64 is screw-threaded to ring e^4 and has an annular shoulder 65 to bear

against the flange d' on the upper end of the casing d . A ring 67 is confined in the coupling ring 64 above a shoulder 68, so that when the injector is being removed, the ring 64 will engage the ring 67 to forcibly withdraw the casing d and the parts sustained thereby from the cylinder head. The nozzle retaining sleeve d^7 is provided with a tapered shoulder 73 which engages a corresponding seat 74 in the extension c^{13} of the cylinder-head C to form a fluid-tight connection between them. The coupling ring 64, engaging the flange d' , jams the casing d downwardly in said extension to maintain a fluid-tight fit between shoulder 73 and seat 74. The upper end of the valve stem is formed at 55 to serve as an abutment to engage an adjustable stop screw 56 to limit the range of movement of the valve stem and correspondingly vary the volume of the charge of fuel injected during each opening of the valve.

In operation, the charges of fuel pumped through the pipe d^{22} will be forced through chamber 41 and port 42 to groove 43 in the valve stem. Thence, the fuel will flow around the grooved portion 44 of the valve stem and through the inclined cross-port 46 and the ports 47, 47' to the chamber 48 from which it will flow through the grooved portion d^3 of the valve stem to the nozzle d^4 . The fuel in chamber 48, when it is subjected to the predetermined pressure desired, will act against the diaphragm d^9 and against the force of spring d^{15} and open the needle valve to inject a charge of fuel into the combustion chamber of the cylinder. The injector is more fully illustrated and described in an application (Case A), Serial No. 18,881, filed by me March 26, 1925, to which reference may be had for further details thereof.

The mechanism for feeding fuel under pressure to the cylinders of the engine constitutes a unit which is enclosed in a casing adapted to contain lubricant and which may be connected as a unitary structure to the engine casing. This makes it possible to readily mount and demount the fuel feeding mechanism. This mechanism is illustrated and described in an application (Case C), Serial No. 32,550, filed by me May 28, 1925, to which reference may be had for the details thereof. The casing for this mechanism is formed of vertically arranged sections and comprises a horizontally extending hollow base member g' which is bolted at g^2 to the crank case of the engine and is provided with an upwardly extending integral cylindrical member g^5 ; a hemispherical section g^4 , which is bolted to the top of member g^3 and contains the mechanism for operating the fuel pumps; a cylindrical section g^5 , in which the pitmen for operating the pumps are contained and which is bolted to section g^4 ; a section g^6 , in which are mounted the fuel pumps and the metering devices; and a

cover g^2 , which is removable to provide access to the mechanism for operating the metering devices as more fully set forth in said application Serial No. 32,550.

5 A vertically disposed shaft (not shown) is adapted to drive the fuel pumps and mechanism for operating the metering devices and this shaft is driven by a horizontal shaft H^2 which extends forwardly through the 10 casing section g' and journaled in a ball-bearing h^{14} at the front of said casing section and also at the rear thereof. A sprocket pinion h^{15} , keyed to the front end of shaft H^2 , is driven by a suitable chain 15 from the shaft 27 in the crank case of the motor. This gearing drives the fuel feed mechanism in synchronism with the engine. As illustrated in said application, Serial No. 32,550, each fuel pump in the 20 casing G, under control of a metering device, is adapted to force successive charges of fuel through a pipe d^{22} which is connected to one of the injectors D. Said pipes are all arranged to have a constant downward slope 25 from the pump to the injector to prevent the formation of air pockets in the fuel, which are likely to render irregular the volume of the charges delivered to the injectors. A desideratum in engines of this 30 type is to insure the injection of uniform volumes of fuel and by forming these pipes with a constant downward trend, the formation of air pockets is prevented.

The invention exemplifies a multi-cylinder engine with a unitary structure containing all of the elements of the fuel feed mechanism which is vertically disposed at one side of the engine casing and which may be readily attached thereto and detached therefrom. The invention also exemplifies an engine in which the fuel feeding mechanism may be connected to a four cycle sleeve-valve type of engine as an attachment.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. The combination of an internal combustion engine comprising a casing and a series of cylinders, a fuel injector for each cylinder, a plurality of sleeve-valves in each cylinder, a shaft driven by the engine for operating said sleeve-valves, and enclosed fuel feed mechanism removably secured to the casing, and gearing driven by the shaft for driving the fuel feed mechanism.

2. The combination of an internal combustion engine comprising a casing and a series of cylinders, a fuel injector for each cylinder, a plurality of sleeve-valves for each cylinder, a shaft driven by the engine for operating said sleeve-valves, an enclosing and supporting casing containing fuel-feed mechanism at one side of the cylinders and removably secured thereto, and gearing driven by the shaft for driving the fuel-feed mechanism.

3. The combination of a multi-cylinder internal combustion engine comprising a casing, an enclosing and supporting casing containing fuel-feed mechanism, disposed at one side of the engine casing and removably secured thereto, a fuel injector in each cylinder, and pipes leading from the enclosing casing to the injectors respectively, said pipes being downwardly inclined from the casing to the injectors.

4. The combination of an internal combustion engine comprising a casing and a series of cylinders, a fuel injector for each cylinder, a casing disposed at one side of the engine casing and having a portion thereof extending above the injectors, fuel feed mechanism in said casing and comprising pumps, outlets for the pumps disposed above said injectors, and pipes leading from said outlets to the injectors respectively, said pipes being inclined downwardly at a substantially constant slope.

Signed at Chicago, Illinois, this 24th day of March, 1925.

AAGE E. WINCKLER.
